(57) CLAIM

The ornamental design for a set of golf club heads, as shown and described.

DESCRIPTION

FIG. 1 is a toe end perspective view of a set of golf club heads showing our new design;

FIG. 2 is a heel end perspective view thereof; and,

FIG. 3 is a bottom view thereof.

The broken lines immediately adjacent the shaded area form unclaimed boundaries of the design. The broken line showing of the remainder of the golf club heads is for illustrative purposes only and forms no part of the claimed design.
